UNITED STATES PATENT OFFICE.

BILLY S. McCAIN, OF MONROE CITY, INDIANA, ASSIGNOR OF ONE-HALF
TO J. W. JONES, OF MONROE CITY, INDIANA.

SHIPPING-CRATE.

No. 827,877.

Specification of Letters Patent.

Patented Aug. 7, 1906.

Application filed December 7, 1905. Serial No. 290,788.

To all whom it may concern:

Be it known that I, BILLY S. McCAIN, a citizen of the United States, residing at Monroe City, in the county of Knox and State of Indiana, have invented certain new and useful Improvements in Shipping-Crates, of which the following is a specification.

This invention relates to an improved shipping-crate of that type which are adapted to be knocked down or collapsed when not in use.

The object of the invention is to provide a crate of this character which will occupy a minimum amount of space when folded, which can be easily and quickly set up, and which will be so rigid as to eliminate all possibility of accidentally collapsing when in use.

For a full description of the invention and the merits thereof and also to acquire a knowledge of the details of construction of the means for effecting the result reference is to be had to the following description and accompanying drawings, in which—

Figure 1 is a perspective view showing the crate in an open position. Fig. 2 is a longitudinal vertical section taken through the crate when open. Fig. 3 is a transverse sectional view, the crate being folded. Fig. 4 is a similar view through one of the ends 30 when the crate is unfolded. Fig. 5 is a similar view through the intermediate partition, and Fig. 6 is an inside elevation of one of the sides.

Corresponding and like parts are referred to in the following description and indicated in all the views of the drawings by the same reference characters.

The numeral 1 designates the bottom of the crate, which is provided at its ends with notches 2, and 3 the ends of the crate, which are hinged to the bottom 1. For this purpose strap-hinges 4 are provided, the upper portions of which serve as a reinforcing means for the end portions 3, while the lower portion of the hinges fit in the notches 2 and are bent around and secured to the bottom 1. The sides of the crate are each formed in two sections, the lower section being rigidly secured to the bottom 1, while the upper section is connected to the lower sections by means of strap-hinges 5. The upper part of the strap-hinges extend along the sides and serve as a reinforcing agent, while the lower end is bent around and secured to the

bottom of the crate. The lower portion 6 of one of the sides is of a suitable height to permit the upper section 7 to fold over upon the ends 3, while the lower section 9 of the opposite side is of such a height as to permit the upper section 9 to fold over upon the upper section 7 of the opposite side. Angle-pieces 10 are secured to the opposite ends of each of the upper sections 7 and 9 of the sides. One of the sides of the angle-pieces 10 serves as a stop-flange 11 to engage with the ends 3 when the latter are open, while the opposite sides of the angle-pieces 10 are provided with notches 12. Headed pins or studs 13 project from the ends of the members 3 and are so arranged that the shanks 70 thereof will enter the notches 12. The portions of the sides below the notches 12 are recessed at 14 for the reception of the heads of the studs 13. Since the heads of the studs 13 will not pull through the notches 12, it will be apparent that the sides and ends of the crate will thus be held in a close engagement with each other. It will be observed that the mouths of the notches 12 are flared outwardly, and thus serve to guide the stud 80 13 into the throat or contracted portion.

In order to hold the ends 13 securely against the stop-flanges 11 when the crate is distended, spring-catches 15 are provided. These catches 15 are preferably formed from a single strip of spring metal, one end of which is secured to the side of the crate, while the opposite end is bent inwardly to form a shoulder which fits against the ends 3. It will thus be apparent that when the ends 3 90 are folded outwardly the catches 15 will permit them to swing into engagement with the stop-flanges 11 and will hold them in the latter position until the spring-catches are pressed inward by some external force. 95 Transverse strips of metal 16 are secured at corresponding points to the upper sections 7 and 9 of the sides of the crate and are provided with angular notches 17. The upper portion of the notches 17 is approximately 100 horizontal and flares outwardly to form a mouth, while the lower portion of the notches is approximately vertical and is contracted to form a throat. A partition 18 is provided at its ends with headed studs 19, similar to the studs 13 and which are adapted to fit into the notches 17 when the partition is in position. For this purpose the portion of the

sides under the notches 17 are recessed to receive the heads of the studs 19. The cover to the crate comprises a light piece of wood 20, which fits over the top thereof. A strip 5 of flexible material, such as sheet metal, is secured to the edges of the wooden cover 20 and forms a flange 21, which fits around the top of the crate.

From the foregoing description it will be 10 evident that when the crate is distended the side pieces and ends will be held rigidly in engagement with each other. The studs 13 and notches 12 will operate with each other to prevent the sides from swinging outwardly 15 or away from the ends 3, and the stop-flanges 11 and the spring-catches 15 will coöperate to prevent the ends 3 from swinging out of position. When the crate is folded, the various members will fit closely against each 20 other, owing to the special formation of the sides, and will occupy a very small amount of space. Attention may also be directed to the fact that the portions of the strap-hinges 4 and 5 which are secured to the bottom 1 25 will hold the latter member rigidly in position and prevent any danger of its sagging or dropping out of position should the crate be filled with heavy material. It will thus be understood that all the various parts of the 30 crate coöperate with each other to secure a very rigid construction and one which will withstand any hard usage to which it may be subjected.

Having thus described the invention, what 35 is claimed as new is—

1. In a device of the character described, the combination of a bottom, ends hinged to the bottom and adapted to be folded thereagainst, a pair of oppositely-disposed sides 40 adapted to fold inwardly, an angle-piece secured to each end of each of the sides, one of the flanges of each of the angle-pieces fitting against the inner face of the side and being provided with notches, the portions of the

side under the notches being recessed, while 45 the opposite flange projects inwardly and forms a stop for the ends, headed studs projecting from the ends and adapted to enter the before-mentioned notches to hold the ends and sides together when the crate is distended, and spring-catches for holding the ends against the stop-flanges when the crate 50 is distended.

2. In a device of the character described, the combination of a bottom, ends hinged to 55 the bottom and adapted to be folded thereagainst, a pair of oppositely-disposed sides adapted to fold inwardly, an angle-piece secured to each end of each of the sides, one of the flanges of each of the angle-pieces fitting 60 against the inner face of the side and being provided with notches, while the opposite flange projects inwardly and forms a stop for the ends, headed studs projecting from the ends and adapted to enter the before-mentioned 65 notches to hold the ends and sides together when the crate is distended, means for holding the ends securely against the stop-flanges, transverse strips secured at corresponding points to the opposite sides of the 70 crate, the said strips being provided with angular notches, one portion of each of the notches extending longitudinally along the strip, while the opposite portion has a lateral direction and forms a mouth leading into the 75 longitudinal portions, and an intermediate partition provided at its ends with headed studs which coöperate with the angular notches in the before-mentioned strips to hold the intermediate partition removably in 80 position.

In testimony whereof I affix my signature in presence of two witnesses.

BILLY S. McCAIN. [L. S.]
